SNAP-ACTION LATCH FOR WORK
HOLDING VISE

Homer G. Luft, Dearborn, Mich.

Application September 11, 1944, Serial No. 553,647

2 Claims. (Cl. 81—25)

1

My invention pertains to improved latching, locking or holding means for drawing and/or securing relatively movable parts together.

It is an object of my invention to provide holding means which will be of a simple rugged construction, and which will be reliable and positive in its action.

It is also an object of my invention to provide improved holding means comprising latch means having a quick snappy action to facilitate repeated operations thereof.

It is a further operation of my invention to provide holding means which will be free and convenient in its operation and which may be operated quickly to apply firm pressure on parts to be held together.

Further objects and advantages are within the scope of my invention, such as relate to the arrangement, operation and function of the related elements of the structure, to various details of construction and to combinations of parts, elements per se, and to economies of manufacture and numerous other features as will be apparent from a consideration of the specification in conjunction with the drawings disclosing specific embodiments of the invention, in which:

Fig. 1 is a front elevational view showing my improved quick lock or latch, as applied on a jig for holding work;

Fig. 2 is a plan view thereof;

Fig. 3 is a side elevational view of the right-hand side, the clamp being shown dotted in several positions;

Fig. 4 is a front elevational view, partially diagrammatic, the manual control and latch being shown dotted in several positions;

Fig. 5 is an enlarged longitudinal sectional view taken on line 5—5 in Fig. 3 showing the self-setting and quick removable pivot bolt for the clamp arm of the jig; and

Fig. 6 is an enlarged cross-sectional view on line 6—6 in Fig. 5.

Referring more specifically to the Figs. 1 through 4 of the drawings, I have illustratively disclosed my improved quick lock or latch as utilized on a jig or fixture for quickly receiving and firmly holding a tubular work piece 11 while it is being drilled transversely by a drill 13. The rigid structure or body of such a jig may be conveniently fabricated from a pair of angle iron pieces 15 firmly clamped together in spaced relation on opposite sides of a hollow square iron 17 by means of bolts 19. The upturned edges of the angle irons 15 are provided with notches 21 and 23 of V or any other shape suitable to accommodate work pieces to be held.

2

A clamp arm 25 is pivotally disposed for clamping down over the notch 23 to hold the work piece. For this purpose the rear end of the clamp arm is suitably apertured to pass a pivot pin 27 there-through and also through the upper ends of a pair of links 29 the lower ends of which are pivotally disposed upon the ends of a pin 31 passing through the end of the angle iron 15 to the rear of the notch 23. The clamp arm 25 may be conveniently lifted, or even turned back, to various positions, as represented dotted in Fig. 3, while changing work pieces. The under side of the clamp arm 25 is also provided with a notch 33 above the notch 23, and this notch is preferably provided with an inwardly directed work gripper 35. To guide the drill 13 accurately into the work piece, the inner side of the clamp arm 25 is suitably recessed to receive a suitably apertured insert 37 of hardened steel, which is replaceably pressed or secured therein in any suitable manner. To receive the sharp lower end of the drill 13, after it has pierced the work 11, I provide a piece 39, of softer iron, or other metal, on the upper end of a screw 41 which passes through an aperture between the square iron 17 and the adjacent angle iron 15, from the bottom of which it can be adjustably raised or lowered.

For quickly and firmly securing the clamp arm 25 down upon a work piece 11, a manual latch 30 control element 43 is provided. The latch control element 43 is a heavy and strong element and it is rotatively mounted upon a heavy pivot pin 45 on the front end of the clamp arm 25. Although the latch control element may be made of various suitable shapes, I preferably make it of a substantially disc shape having an aperture in its central portion for mounting upon the pivot pin 45. A handle extension 47 is preferably integral with the latch control element 43 and it extends from a suitable side for convenient manipulation.

A second pivot pin 49 is provided secured rigidly into the control element 43 with its axis parallel to and spaced from the axis of the main support 45 pivot 45 for receiving one end of a latch lever 51 and supporting it for rotation in a plane parallel to the control disc 43. The other end of the latch carries, extending from one side in the plane of rotation of the latch, a hook extension 53, for 50 engaging and drawing on the remote side of a rigid projection 55 which is carried by the stationary structure of the adjacent angle iron 15. With the hook 53 engaged under the projection 55, rotation of the handle 47 clockwise draws the clamp arm 25 down on the work due to the crank action of the pivot pin 49 displaced from the axis of ro-

tation in the center of pin 45. By having the latch 51 of a proper length with the hook 53 suitably disposed so that all the slack is taken up just as the crank pin 49 moves over or above the main pivot pin 45, the work is secured and held very firmly. To facilitate obtaining and maintaining this condition with various work pieces, or under conditions of wear, the hook 53 may be provided with a contact screw 57 whereby contact with the lower side of the projection 55 is adjusted as desired and the screw is secured by a lock nut 59. As shown in Fig. 3, to provide for further adjustment or taking up wear, the projection 55 is preferably an extension of a plate 61 replaceably secured by screws 63 and pilot pins 42 on the side of the angle iron 15 which may be cut in to provide a shoulder 65. In this manner plates 61 can be removed and replaced in accordance with the required condition of the projection 55. As shown in Fig. 1, projection 55 is so mounted that it clears the arcuate portion 67 of the latch control element 43, but at one end of the arc 67 is a projection 69 of greater radius which engages the projection 55 and limits the rotation of handle 47 in the latched or locked position. The latch control element 43 is also provided with another radially extended portion 71, at the opposite end of the arc 67, which at times abuts a pin 73 mounted stationary on a plate 75. The plate 75 has a flange 77 secured to the inner side of clamp arm 25 by rivets 76 which also hold a plate 78 on the outer side. The lower ends of flange 77 and plate 78 project down over the upturned web of the adjacent angle iron 15 on opposite sides thereof to guide the clamp arm 25 accurately to a proper lateral position.

A snap action spring 79 has one end secured, as by an anchor plate 81 to the end of a pin 83 on an intermediate portion of the latch 51. The other end of the spring 79 is secured up on the control disc 43 in a suitable position to cause the latch 51 to snap toward or away from the projection 55 as the handle 47 is swung in one direction or the other. For this purpose I provide a lever 85 having an elongated slot 87 loosely mounted on a screw or pin 89 secured in control disc 43 and having one end of lever 85 secured by a pivot pin 91 to a lug 93 on the upper end of the latch 51. The other or free end of the lever 85 carries a pin 95 whereupon the upper end of the spring 79 is secured. For protection thereof, suitable enclosure means may be provided to cover the latch and snap action mechanism, as will be understood.

Fig. 4 shows in full line the handle 47 turned up in the unlatched position, as though a work piece 11 had just been inserted. The handle 47 is then turned clockwise toward the position B represented dotted. The spring holds the latch firmly against the stationary pin 73, in unlatched position until the latch 51 and the lever 85 are turned in straight alignment and just slightly beyond. Then the latch snaps against the projection 55 with the hook 53 disposed thereunder, as represented dotted. Continued movement of the handle 47 in a clockwise direction draws up the hook 53 against the underside of the stationary projection 55 drawing the clamp arm 25 firmly down on the work piece. All the slack is snugly taken up just as the pivot pin 49 passes above the main pivot 45 whereby a slight effort on the handle provides a great clamping force and the clamp remains securely locked.

Fig. 5 shows the details of the self setting and quick releasable pivot pin 31 which I have de-

vised for insertion through the angle iron 15 to hold the lower ends of the links 29 from the clamp arm. This releasable pivot pin comprises a tubular shank 95 having a head 97 at one end wherein an enlarged counter-bore 99 houses a compression spring 101. Slidably disposed in said shank is a stem 103 having a head 105 compressing upon the spring 101. The inner end of the stem 103 is slotted or bifurcated forming a fork to receive a curved finger 107, pivotally secured therein on a pin 109, as shown in more detail in Fig. 6. The side of the tubular shank 95 is provided with a slot 111 opening therethrough, and acting to cam the end of the curved finger outwardly as the spring pushes the head outwardly. To release, smaller head 105 is pushed into the larger head 97 which draws the finger in. The pivot may then be inserted. After insertion, the head 105 is released and the spring throws the finger out in a latching position to secure the pin in any aperture wherein it has been inserted. The inner end of the tubular shank 95 is threaded a short distance to receive a screw 113 for closing the end of the passage, and for limiting the inward movement of the stem 103 so that the finger 107 will be retracted into the slot 111 but not all the way thereinto, as shown dotted. To disassemble, the screw 113 is removed so that the stem 103 can be pushed further into the tubular shank for completely retracting the finger 107 into the fork in the end of the stem, as represented. The stem 103 may then be drawn from the shank. The surfaces of the large head 97 may be suitably shaped or knurled to facilitate gripping between two fingers while pushing in the smaller head 105.

Although I have shown my locking or latching means on a work holding jig, in the specific embodiment disclosed, it will be understood that it also may be applied with equal utility and advantage in a great many situations where there are relatively movable members, or a stationary structure and a movable member which are to be firmly, quickly and conveniently secured together.

It is apparent that within the scope of the invention modifications and different arrangements may be made other than herein disclosed and the present disclosure is illustrative merely, the invention comprehending variations thereof.

I claim:

1. Snap action holding means comprising, a stationary structure, a member movably secured to said structure, a latch control disc having a central aperture, a pivot passing into said member through said aperture in the control disc for pivotally securing said disc on a portion of said member which is movable toward or away from said structure, a second pivot secured in and extending from said disc in a relation axially spaced from and parallel to the first mentioned pivot, a latch having an apertured end pivotally mounted on said second pivot on said disc, the free end of said latch having a hook projection extending therefrom in the plane of rotation of the latch, a projection extending from said stationary structure to be engaged by said latch and its hook projection when the member is adjacent the structure, a spring secured at one end to an intermediate portion of said latch, a lever, means pivotally securing one end of said lever to the pivoted end of the latch, means securing the other end of said spring to the free end of said lever, a slide connection means between said disc and said lever for turning the lever relatively to the

latch to draw the spring to one side or the other and to snap the latch to one side or the other as the disc and the latch are relatively rotated, and a stop for engaging the latch on the side opposite from the side which engages said stationary projection for holding the latch and limiting its movement relative to the disc as the latter is rotated on its pivot.

2. Snap action holding means in accordance with claim 1 and further characterized by said disc having a pair of projections extending outwardly from its edge or rim in suitably spaced positions so that one of said projections engages the stop when the disc is in unlatched position and the other projection from the disc engages the projection from the stationary structure when the disc is in the latching position.
